UNITED STATES PATENT OFFICE.

EMIL OFFENBACHER, OF MARKTREDWITZ, GERMANY.

DESIGN FOR DECORATIVE SHEET-GLASS REPRESENTING GLASS PANELS.

44,933.

Specification for Design.

Patented Nov. 25, 1913.

Application filed December 21, 1912. Serial No. 738,073. Term of patent 14 years.

To all whom it may concern:

Be it known that I, EMIL OFFENBACHER, a subject of the German Emperor, residing at Marktredwitz, Bavaria, Germany, have invented a new, original, and ornamental Design for Decorative Sheet-Glass Representing Glass Panels, of which the following is a specification, reference being had to the accompanying drawing, forming part thereof.

Figure 1 is a top plan of the plate glass.

Fig. 2 is a sectional view of the plate glass showing the depth of the grooves.

I claim—

The ornamental design for decorative sheet glass representing glass panels as shown.

EMIL OFFENBACHER.
